UNITED STATES PATENT OFFICE.

LOUIS J. NEWMAN, OF NEW ROCHELLE, NEW YORK.

RESILIENT WHEEL.

Application filed July 16, 1919. Serial No. 311,309.

To all whom it may concern:

Be it known that I, LOUIS J. NEWMAN, a citizen of the United States, and residing in the city of New Rochelle, Westchester County, and State of New York, have invented certain new and useful Improvements in Resilient Wheels, of which the following is a specification.

This invention relates to resilient wheels in which an inner axle contacting unit is connected to an outer tread unit by means which yieldably resist a departure of these units from concentric relation to each other. The object of the present invention is to provide an improved construction for wheels of this character for securing a better distribution of stresses and a more efficient absorption of shocks and jars under practical running conditions on the road. As exemplified in the drawings, these wheel units are preferably connected by link and levers which are normally under sufficient pressure or tension to retain said units in concentric relation under normal load conditions, such pressure or tension however permitting a departure from concentric relation under any abnormal conditions of load such as those produced by any irregularities of the road. Another object is to provide an improved link and lever system for suspending the axle contacting unit within the tread unit by means of resilient units in such a way that every movement of said units out of concentric relation to each other will be counteracted by the majority of the levers and links in said system under the action of said resilient units. Other and further objects will appear in the specification and be pointed out in the appended claims, reference being had to the accompanying drawings which exemplify my invention and in which:

Figure 1 is a side elevation of a wheel constructed in accordance with the principles of the present invention parts being broken away and parts shown in section.

Figure 2 is a section on the line II—II of Figure 1.

Figure 3 is a section on the line III—III of Figure 1.

Figure 4 is a section on the line IV—IV of Figure 1.

Figure 5 is a plan view of one of the reverse levers detached.

Figure 6 is a side elevation of the same.

Figure 7 is a diagram showing relative

positions of the several parts when the wheel units are out of concentric relation.

Figure 8 is a fragmentary side elevation of another embodiment, parts being shown in section.

Figure 9 is a sectional view of the cylinders corresponding to an eccentric position of the wheel units.

Figure 10 shows a modification in the link connections.

In the embodiment of my invention shown in Figures 1 to 6 of the drawings an axle contacting unit is constructed to embody a hub portion 1, radial spokes 2, and axially spaced rings 3. The outer ends of each of said spokes 2 are preferably bifurcated to form bearings 4 for a pin 5 upon which is journaled the hub portion 6 of one of a plurality of double ended levers. As shown in Figures 5 and 6, each of said levers comprises the hub portion 6, an arm 7 of uniform cross section throughout and an arm 8 which is bifurcated at its outer end to form branches 9 which are adapted to straddle the arm 7 of the adjacent lever of the system. According to this embodiment of my invention the arms 7 and 8 of each of these levers are deflected inwardly toward the center of the wheel from a tangent through the axis of pivot pin 5. As shown in Figure 1, the arm 7 and the branches of arm 8 overreach each other and have a common bearing on a roller 10 journaled on a pin 11 in the outer end of a rod 12. In order to provide suitable and efficient means for yieldably holding said levers against displacement in either direction and under an initial tension which does not involve two opposed forces operating on a single lever, my invention contemplates in the present embodiment, a piston 13 which reciprocates in a cylinder 14 under the action of any suitable pressure medium such for example as the spring 15 or fluid contained in cylinder 14 or both of these mediums. The cylinder details as well as the character of the pressure medium for operating the piston therein exemplify suitable resilient means for counteracting radial movements of the rods 12. As shown best in Figure 6, the arm 8 of each of said levers is provided with an apertured boss 16 which as shown in Figure 2 carries a pin 17 to which are pivotally connected the inner ends of link members 18. The outer ends of said link members 18 are pivotally connected to pins 19

100
105
110

which are mounted on the inner periphery of a tread unit comprising a rim 20 and tire 21. By an inspection of Figure 1, it will be seen that the system of links and levers 5 which serve to suspend the axle contacting unit within the tread unit, comprises a circular series of double ended levers with over-reaching arms extending substantially continuously around the outer periphery of 10 the axle contacting unit, (and in the preferred embodiment herein shown) between the axially spaced rings 3. As shown on the drawings, each link 18 connects the bifurcated arm 8 of one of said levers to the 15 tread unit. It will be understood from this description, that each of the pins 17 constitutes a floating fulcrum for one of the levers while the resiliently mounted rollers 10 operating on one or the other arm of said 20 lever constitutes a yielding force which tends to maintain the loaded axle contacting unit concentric with the tread unit. In each instance the pin 5 constitutes one of the points of suspension of the axle contacting unit. In this connection, it is to be noted that at all times most of the resilient units in the wheel are brought into play for counteracting the tendency of the wheel units to depart from concentric relation and 25 the combined effect of all of these resilient units acting through the lever system to maintain a normally loaded axle contacting unit in concentric relation to the tread unit. It will be seen from an inspection of Figure 1 that in their outermost positions, the pistons 13 are held under initial pressure by means of the outer ends of cylinders 14. Such initial pressure or tension may obviously be made of any desired intensity to 30 adapt the mechanism to retain the wheel units in approximate concentric relation under any desired conditions of normal running load. It will be obvious that the invention as disclosed herein is applicable to a 35 wheel in which the units are capable of relative lateral tilting movements with respect to each other such as would be the case if the links 18 were provided with ball and socket joint connections with both of said units. 40 Such a construction is shown in Figure 10. In the embodiment of my invention shown in Figures 8 and 9, the tread unit 22 is connected to the peripheral portion 23 of the axle contacting unit by means of links 24 and a circular series of lever arms 25 which are pivoted at 26 to the axle contacting unit. According to the preferred embodiment of my invention shown in Figures 8 and 9, in 45 each resilient unit there are three telescopic cylinders. An intermediate cylinder 27 is pivotally connected at 28 to the hub 29 of the axle contacting unit. The lateral wall of this cylinder is provided with slots 30 which serve as guides for pins 31 carried by 50 the innermost cylinder 32 which is adapted

to have its bottom abut against the bottom wall of the cylinder 27. Slidably mounted in the cap 33 of the innermost cylinder 32, 55 is a piston rod 34 which carries a piston 35, said piston being confined between the cap 33 and the bottom wall of cylinder 27. A resilient medium in the form of a compression spring 36 is interposed between the piston 35 and the bottom wall of said cylinder 32, 60 and tends to hold said piston in the position shown in Figure 8. The intermediate cylinder 27 is provided with a cap 37 which also has slidable contact with the piston rod but is limited to relative displacement the amount of which is determined by a nut 38. 65 The outer end of the piston rod 34 is adapted to removably abut against the cap 39 of the outermost cylinder 40 which is pivotally connected at 41 to the outer end of lever arm 25. The inner end of cylinder 40 is contracted at 42 to slidably engage the outer wall of intermediate cylinder 27 without interfering with the movements of pins 31 along the slots 30. As shown in Figure 10, 70 the tread unit 43 of the wheel may be provided with a socket 44 for receiving a ball 45 on one end of a link 46, the other end of said link being also provided with a ball 47 which operates in a socket 48 carried by 75 the lever arm 49. This construction permits a relative lateral tilting of the wheel units 80 with respect to each other.

While Figure 10 shows the universal link 46 applied to a lever having an arm shaped somewhat similarly to lever arm 25 shown 85 in Figure 8, obviously the lever 49 may have either one or two arms, depending upon the type of wheel to which the link is applied.

From the above description, the advantages to be derived from my invention, will 90 be readily understood from its operation. As shown in Figure 1, the wheel units are in concentric relation to each other under normal conditions of load such as will be the case with a truck or car constructed according to this invention, when it is standing or moving over a smooth surface. The tension in spring 15 or other pressure medium has been predetermined so that it will 95 be more than sufficient to support the load under the above referred to conditions with the wheel units concentric. Referring now to the diagram shown in Figure 7, it will be seen that when the axle unit drops into an eccentric position with respect to the tread unit, that the movement is resisted by five out of the six resilient units. It will be understood in this connection, that each of the five units is exerting a resilient tendency equal to the initial tension of the unit including the excess pressure against the cap of the cylinder under normal concentric conditions. Substantially the same action occurs in resisting any relative movements 100 between the wheel units due to torsional ef-

fects, so that this wheel may be readily adapted for driving vehicles on which it is mounted. In the embodiment shown in Figures 8 and 9, whenever there is a downward eccentric movement of the axle unit with respect to the tread unit, the movement is absorbed by the resilient units in the manner indicated in Figure 9, according to which the intermediate cylinder by moving with the axle unit, causes cap 37 to depress the piston rod 34 which forces piston 35 downwardly under action of the spring 36. Various modifications in the construction and arrangement of the several elements with respect to the axle and tread units may be embodied without departing from the spirit of my invention which contemplates the simultaneous cooperative action of an entire group of resilient units which tend to retain said units in concentric relation. For example, it is obvious that the resilient units may be mounted on the tread unit just as well as on the axle contacting unit, in which event the levers and links would be arranged in reverse order from that shown on the drawings.

I claim:—

1. The combination in a vehicle wheel of a rigid circular outer member connected through a system of links, levers and pivots to a symmetrically shaped rigid inner member, a set of resilient elements interposed between the outer and inner members through the system of links, levers and pivots, the whole arranged in such a manner that the weight applied through the hub is supported in suspension by the upper half of the outer member through the system of links, levers and pivots acting against the sustaining force of the resilient elements as well as carried directly by the lower half of the outer member through the system of links, levers, and pivots acting against the sustaining force of the resilient elements, the majority of the resilient elements being in effective action in every position of the wheel to sustain the load.
2. In a resilient wheel, an axle contacting unit, a tread unit, a plurality of levers pivotally mounted on one of said units, angularly spaced resilient units, each of said resilient units being arranged to oppose the

adjacent ends of two different levers, and means for articulately connecting said levers to the other of said units. 55

3. In a resilient wheel, a tread unit, an axle contacting unit, a plurality of levers pivotally mounted on said axle contacting unit, resilient means mounted on said axle 60 contacting unit for operably engaging either end of each of said levers, and a floating fulcrum suspended from said tread unit for each of said levers.

4. In a resilient wheel, a tread unit, an 65 axle contacting unit provided with a plurality of angularly spaced resilient units, a plurality of levers pivotally mounted on said axle contacting unit and each comprising oppositely projecting arms arranged to 70 bear on different resilient units, and links pivotally connected to said tread unit and providing floating fulcrums for the levers connected thereto.

5. In a resilient wheel, a tread unit, an 75 axle contacting unit provided with a plurality of angularly spaced resilient units, a plurality of levers pivotally mounted on said axle contacting unit and each comprising oppositely projecting arms adapted to 80 bear on different resilient units, and links pivotally connecting said tread unit to said levers, the oppositely presented arms of adjacentely disposed levers being arranged to overreach each other and to engage the same 85 resilient means.

6. In a resilient wheel, a tread unit, an axle contacting unit provided with a plurality of angularly spaced resilient units, a plurality of levers pivotally mounted on said 90 axle contacting unit and means for connecting each of said tread units to said levers with a universal movement.

7. In a vehicle wheel, the combination with a tread unit, of an axle contacting unit, 95 one of said units being provided with a plurality of angularly spaced resilient units, and a system of links, levers and pivots for connecting said tread and axle contacting units and operating on said resilient units, 100 the majority of said resilient units being in effective action for opposing relative displacement between said units in every position of the wheel.

LOUIS J. NEWMAN.
